UNITED STATES PATENT OFFICE

157,248

HAIRBRUSH

Kenneth C. Fay, New York, N. Y., assignor to Par-fumerie De Raymond, New York, N. Y., a firm

Application March 3, 1949, Serial No. 1,178

Term of patent 7 years

(Cl. D86—10)

To all whom it may concern:

Be it known that I, Kenneth C. Fay, a citizen of the United States of America, residing at New York, in the county of New York and State of New York, have invented a new, original, and ornamental Design for Hair Brush, of which the following is a specification, reference being had to the accompanying drawings, forming part thereof, and wherein:

Fig. 1 is a side elevational view of a hair brush showing my new design;

Fig. 2 is an end elevational view thereof; and
Fig. 3 is a top view thereof.

I claim:

The ornamental design for a hair brush, substantially as shown.

KENNETH C. FAY.
